CONTROL DEVICE FOR ELECTRICAL CIRCUITS

Harry C. Warner, San Francisco, Calif.

Application September 2, 1949, Serial No. 113,753

21 Claims. (Cl. 179—100.41)

1

This invention relates to an improved control device for electronic circuits. More particularly it relates to such control devices as phonographic sound reproducing apparatus and microphones, especially to new and novel types thereof employing a liquid current-modulating medium. The present application is a continuation-in-part of application Serial No. 738,159, filed March 29, 1947, now abandoned.

The invention solves such problems in pickups as the elimination of distortion, the transmission of a wide range of well-modulated frequency responses, and reduction of needle scratch to a negligible amount. It accurately transmits the mechanical variations in frequency and amplitude (recorded in the record groove) into corresponding variations in electrical current. It is fully responsive to the lateral variations of the record groove, but it is relatively unresponsive to vertical variations, which are aberrations and if transmitted cause undesirable extraneous noises. Needle scratch, for example, is caused mostly by such vertical aberrations traceable to roughness in the bottom surface of the record groove.

In the present device these vertical aberrations are cancelled out and are not present in the output. In addition, because of the very excellent fluid damping in the present invention, mechanical resonances traceable to the moving parts are also absent from the output. The invention thus overcomes most of the deficiencies of crystal pickups while still providing a very lightweight relatively inexpensive pickup. It also has great advantage over magnetic pickups because the output current is greater and because the present invention is amplitude-responsive without resonant peaks (instead of velocity-responsive) and therefore requires no compensation for proper reproduction of records. Moreover the simplicity of its structure renders it less expensive, and it can be produced in quantity with the requisite accuracy.

The principles of the invention are also applicable to microphones. Similar problems in that connection are solved by the invention, and an accurately responsive microphone provided.

In general the invention includes a body member of insulating material having three serially adjoining chambers which contain an electrolyte. Each chamber has an electrode and two variable-area orifices are provided to connect one chamber with the other two. Means are provided for varying the area of these orifices in accordance with externally originating motion such as the

2

lateral motion of a phonograph needle or the lateral motion of a microphone-diaphragm. As the orifices vary in area in accord with the motion of the needle or diaphragm, the resistance between the electrodes in each chamber varies. By properly connecting the electrode of the center chamber with one part of an electronic circuit and the electrodes of the outer chambers to other parts, the voltage of the center chamber electrode will be varied in accordance with the originally reproduced sound, and this voltage variation may readily be amplified. With the two outer chambers set to balance each other for vertical variation, the vertical component of the needle's motion can be substantially cancelled from the output.

Other objects, advantages, and uses of the invention will be in part evident to those skilled in the art and in part pointed out hereinafter in connection with the accompanying drawings, wherein preferred embodiments of the invention are shown, by way of illustration and not of limitation.

In the drawings:

Fig. 1 is a plan view of a pickup unit embodying the principles of the invention, with a portion thereof broken away and in section to reveal inner details.

Fig. 2 is a side view of the pickup unit of Fig. 1 taken along line II—II of Fig. 1.

Fig. 3 is a plan view of the bottom portion of the pickup shown in Fig. 1.

Fig. 4 is a vertical sectional view taken along line IV—IV of Fig. 3 looking in direction of the arrows.

Fig. 5 is a slightly enlarged sectional view taken along the central plane longitudinally of the pickup of Fig. 1.

Fig. 6 is a slightly enlarged sectional view taken along line VI—VI of Fig. 1 looking in direction of arrows.

Fig. 7 is a horizontal sectional view taken along line VII—VII of Fig. 5.

Fig. 8 is a vertical sectional view taken along line VIII—VIII of Fig. 5 looking in direction of the arrows, and showing in an exaggerated manner (for purposes of illustration) the effect upon the variable orifices of the sidewise motion of the needle.

Figs. 9 and 10 are diagrammatic views illustrating two circuits by which my improved pickup may be connected to a thermionic tube amplifier.

Fig. 26 is a view of the microphone diaphragm and its associated supporting member which actuates the transmission thereof.

Fig. 27 is a top plan view of a further modified form of control device; the view is somewhat diagrammatic in form and the chuck and some other parts are removed for the sake of clarity.

Fig. 28 is a side elevation view of the device of Fig. 27.

Fig. 29 is a view in perspective of the actuating member or chuck used with the device of Figs. 27 and 28 in a phonographic pickup unit, and

Fig. 30 is a diagram of the circuit used in the device of Fig. 27.

In Figs. 1 to 4, inclusive, is shown the assembly and several of the parts which constitute the principal elements of one form of improved pickup. In connection with this description it will be understood that the pickup unit, here shown in substantially its normal size, will be carried at the free end of a tone arm. The tone arm will be supported so that the unit here illustrated may swing freely and may follow the sound track in a record of the disc type. It will also be understood that if the device should be used in connection with cylindrical or tape types of recording, it will be carried over the cylindrical or tape record in the conventional manner of such machines.

In Figs. 1 to 4 the pickup, designated broadly

by the numeral 10, is shown as comprised of an upper body forming member 11 of insulating material within which two cavities or chambers 12 and 13 are formed. In these a quantity of a suitable liquid or electrolyte 14 may be held. The chambers 12 and 13 are here shown as extending longitudinally of the body member 11 and in spaced parallel relation to each other. Mounted with the body member 11 and interposed between the two chambers 12 and 13 is a cylindrical wall forming member 15. As will hereinafter appear, the wall 15 serves to form a third chamber 16 for containing a further quantity of said liquid or electrolyte 14 within the body member 11.

As is more clearly shown in Fig. 2, the bottom ends of the chambers 12, 13 and 16 are open. The open ends are coplanar, and their plane is normally positioned horizontally. A flexible diaphragm 17, shown across the lower surface of the body member 11, closes the open bottom ends of the chambers 12, 13 and 16. Preferably this diaphragm 17 in the form of a sheet of soft rubber or latex is clamped between the lower side of the body member 11 and a metallic plate 18, by means of screws 19 which are disposed centrally at each end thereof.

A terminal supporting member 20 of insulating material extends outwardly from one end of the plate 18. Terminals 21, 22 and 23 are held in spaced relation on the member 20. These terminals 21, 22 and 23 are respectively connected through conductors 24, 25 and 26 with electrodes 27, 28 and 29 which are disposed respectively within the chambers 12, 13 and 16 of the body member 11. At this point it may be stated that the electrodes 27, 28 and 29 here referred to may be formed by a metallic plating upon the inner vertical walls of the chambers 12, 13 and 16 within which they are respectively disposed. Or they may be in the form of a thin strip of metal foil which is bent to fit within these chambers and remain immersed in the electrolyte 14 with which, as previously suggested, these three chambers are at least partially filled. Or rod or plate electrodes inserted inside the chambers 12, 13 and 16 may be used instead.

As shown in Fig. 2 of the drawing, the unit 10, as a whole, together with the free floating end of the tone arm support (not shown) which carries this unit may be lightly supported by a record engaging needle 30. The needle 30 is adapted to follow the sound track of a disc type record 31 here outlined by dot and dash lines. As will hereinafter appear, the record tracking needle 30 is adapted to operate upon the flexible diaphragm 17 and cause it to be flexed. This flexing causes the orifice openings between the chambers 12 and 16 and between the chambers 13 and 16 to vary in area. When this happens, the current flowing in the electrolyte 14 between the electrodes 27 and 29 and between the electrodes 28 and 29 encounters oppositely varying resistances in the orifice openings, and the result is that the chamber-to-chamber voltage across the orifices will vary correspondingly. In other words this flexing of the diaphragm 17 is adapted to provide for variations in the electrical potential between the electrode 29 and the two electrodes 27 and 28 as the record engaging needle 30 swings from one side to the other in following the sound track upon a record.

In Figs. 3 and 4, the bottom plate 18 of the pickup unit 10 is shown as formed with two elongated recesses 32 and 33. These recesses 32, 33 register with the chambers 12 and 13 formed in the body member 11. At the point 75 where the cylindrical wall-forming member 15

is positioned, there is a deeper recess 34 with a central opening 35 within which a needle supporting member is positioned and held in co-operating relation with the flexible diaphragm 17.

Reference is now made to Figs. 5 and 6 of the drawing for a more detailed description of the manner in which the record engaging needle 30 is supported in cooperating relation with the flexible diaphragm 17. A needle supporting member 36 is here shown in the form of a button or disc-like member. It has a central hub portion 37 into which the upper end of the needle 30 is adapted to be secured either by press fit, as shown, or in the conventional manner by means of a thumb screw, not here shown. The disc-like portion of the needle supporting member 36 also has an upstanding outer annular rim portion 38 which extends into engagement with the under side of the flexible diaphragm 17. This annular rim 38 of the needle supporting member 36 is here shown as slightly larger than the diameter of the cylindrical member 15 which forms the inner chamber 16. When in engagement with the flexible diaphragm 17, this rim 38 will prevent or reduce the flow or contact of electrolyte 14 between the chambers 12 and 13 and the chamber 16. In this particular arrangement the needle supporting member 36 is shown as supported in yielding engagement with the flexible diaphragm 17 by means of a soft rubber cushion 39 which is positioned within the recess 34 of the member 18. As a means for varying the action of the needle supporting member 36 upon the flexible diaphragm 17, it may, as is shown in Fig. 6, provide the member 18 with a pair of oppositely disposed set screws 40 which will engage with a relatively thin annular washer 41 that is freely movable within the recess 34. In this way by adjusting the position of the set screws 40 it will be possible to vary the yielding pressure that will be exerted at the side of the needle supporting member 36 by the soft rubber cushion 39.

For the purpose of describing the operation of my invention, reference is now made to Figs. 7 and 8 of the drawing. As will be seen in the former figure, the cylindrical member 15 which forms the inner chamber 16 is fitted tightly within a central wall forming portion 42 of the body member 11 and in conjunction therewith provides for a permanent seal and obstruction to the flow of electrolyte directly from the chamber 12 to the chamber 13 and vice versa. In other words, any electrolytic contact which is made will be made via the intermediate chamber 16 formed within the cylindrical member 15.

In this connection, it should be mentioned that while the flexible diaphragm 17 is shown in Fig. 8 as flexed outwardly to an extent which might appear to uncover that portion of the cylindrical member 15 which is immediately adjacent the wall 42 of the member 18, this is not the case. In this showing the needle 30 is deliberately shown as off-set to an abnormal degree so as to magnify the degree of flexure of the flexible diaphragm 17, but in actual operation it will be understood that the swing of the needle 30 will be only a matter of a few thousandths of an inch as will be determined by the sound track upon a record. The electrolyte-flow-controlling movements of the diaphragm 17 will also vary in a small degree, which may be plus or minus one one-thousandth of an inch.

Under these conditions (see Fig. 8) it will be seen that as the record tracking needle 30 swings from one side to the other of the medial line of

the pickup unit 10, the needle supporting member 36 will be caused to rock upon its supporting soft rubber cushion 39. The member 36 will then exert more or less pressure against the under side of the flexible diaphragm 17 at the points where the lower edge of the cylindrical member 15 lies within the limits of the chambers 12 and 13. This will alternately establish changes in liquid contact areas between the electrolyte 14 within the chamber 16 and the electrolyte in the chambers 12 and 13.

Therefore when the unit 10 is connected into the input circuit of an amplifier system, and a potential impressed thereupon, the needle movement will cause a modulation of the resistance to the current flow between the electrode 29 in the chamber 16 and the other electrodes 27 or 28 of the chambers 12 and 13. This current flow is indicated by the arrows applied to this figure. It will be also understood that similar conditions of current flow impedance will be subsequently established between the electrolyte 14 in the chamber 16 and the electrolyte 14 within the chamber 12 when the needle 30 is in the other extreme of its swinging movement.

Certain important points in the operation of the device may be noted here. The basis of operation is the varying of orifices between a center chamber and two chambers on either side which are not connected together. The variation of the orifices is produced by the mechanical variation of the needle 30 in the sound track of the record 31. When one orifice (as between chambers 12 and 16) is opened wider, the other orifice (between chambers 13 and 16) is narrowed, and vice versa. Thus a push-pull mechanical variation of the orifice areas is obtained in normal operation on a laterally cut record. The electrical potential of the electrolyte and pickup electrode in chamber 16 will tend to approach the potential of whichever chamber 12 or 13 is at that time connected by the larger orifice. Vertical motion of the pickup needle causes the orifice areas to increase or decrease in unison so that they do not produce any shift in the potential of chamber 16 relative to chambers 12 and 13. This simultaneous operation eliminates the vertical component almost completely, so that all the variation is produced by the lateral movement of the needle. Thus the record groove produces all the electrical effects, and there will be no response to the vertical component of extraneous effects, such as needle scratch. Moreover, the tension on the diaphragm 17 is so adjusted that the conductivity through the orifices between the electrodes varies linearly with the lateral movement of the needle 30.

While no particular type of liquid conducting medium or electrolyte 14 has been specified hereinabove, it may be stated that practically any liquid medium having current conducting characteristics may be employed. In the present instance, since the chambers 12, 13 and 16 are substantially sealed off from the outside, it is important to provide an electrolyte or liquid current conducting medium 14 which will be substantially free from gassing when in operation. I have found that one such electrolyte, which has been found to be admirably suited to the particular structure hereinafter described, may be formed by a solution of cadmium sulphate in ethyl alcohol. This solution is practically non-polarizing, and when used with cadmium electrodes 27, 28 and 29 the device has been found to produce most satisfactory results. This it is

believed may be explained by the fact that cadmium ionizes faster than any other comparable metal. Where the electrodes are of this latter type, I prefer to use thin strips of shim steel of one-thousandth inch in thickness and apply the cadmium plating thereto.

Another suitable electrolyte is a solution of alum (potassium aluminum sulfate) in ethylene glycol. The conductivity of this electrolyte may be increased by the addition of some potassium or sodium iodide. In this instance I have found that the electrodes 21, 23 and 29 may be made from a nickel silver alloy containing about 18% silver. A current conducting gas, such as argon or neon, may also be used as the fluid medium for conducting the modulated current between the several electrodes of the device, as the record tracking needle 30 operates upon the diaphragm or flexible sealing means 17.

In Fig. 9 of the drawing, I have diagrammatically shown my pickup unit 10 constructed as above described in connection with the input circuit of a push-pull amplifier. In this diagram the amplifier is shown as having two input tubes 43 and 44, each of which is of the conventional three electrode type. When my pickup device is used in this manner the electrode 29 will be connected through a source of potential, here provided by a battery 45, to the cathode circuit 46 which feeds into the cathodes of the thermionic tubes 43 and 44. This circuit also includes a conventional cathode bias resistor-condenser assembly 47. The battery 45 is here shown as having its positive side connected to the electrode 29, however the polarity of the battery has no effect on the operation of the pickup. The electrodes 27 and 28 are connected respectively to the control grids of the thermionic tubes 43 and 44. The circuit from the electrode 27 is traced through the conductor 24, a blocking condenser 48, and a conductor 49. Likewise the connection from the electrode 28 may be traced through the conductor 26 to a blocking condenser 50 and a conductor 51, which connects with the control grid of the thermionic tube 43. Bypass resistances 52 and 53 are also provided across the grid to filament circuits of the tubes 43 and 44. Resistors 58 and 59 serve as D. C. return paths for the currents back to the battery.

Fig. 10 diagrammatically illustrates another system of connections by which my pickup unit 10 may be employed with a thermionic tube amplifier of the type having a single input tube. In this instance, as here shown, a potential is impressed across the terminals 27 and 28 of the unit 10 by means of a battery 54, and the electrode 29 is connected through a blocking condenser 55 to the control grid of a thermionic tube 56. The negative side of the source of potential here provided by the battery 54 is shown as grounded, and in this manner the tube controlling circuit is completed through ground to the cathode circuit of the thermionic tube 56.

It is believed, with the above description taken in connection with the diagrammatic showings of Figs. 9 and 10 and the description given in connection with Fig. 8 of the drawing, that the operation of this device will be fully understood by those skilled in the art, and while I have, for the sake of clearness and in order to disclose the invention so that the same can be readily understood, described and illustrated a specific form and arrangement, it is to be understood that the invention is not limited to the specific form disclosed, but may be embodied in other forms and

arrangements that will suggest themselves to persons skilled in the art and it is desired to claim it so that all such changes as come within the scope of the appended claims are to be considered as part of this invention.

A modified form of pickup 60 also embodying the invention is shown in Figs. 11 to 22. This pickup 60 may be used in the same circuits as the pickup 10, or either type of pickup may be used in still different circuits.

The pickup 60 (see Fig. 11) is supported in a housing member 61 which is open at the top and is closed there by a cap plate 62. The pickup 60 includes a body member 63, made from an insulating material, and a pickup chuck 64 which holds the needle 65. In this case the needle 65 is shown as a small sapphire secured to the end of the chuck 64, but other types of needles may be used.

20 The body member 63 is shown by itself in Figs. 21 and 22. In the form shown here it comprises a rectangular block of plastic recessed to provide three chambers 66, 67, and 68 which extend therethrough from top to bottom. The chambers 66, 67, and 68 are preferably parallel to each other and extend for substantially the length of the member 63. They are separated by vertical partitions 69 and 70. The bottom surfaces of the body member 63 and the partitions 69 and 70 terminate bluntly and in the same plane. In the upper side, they also all end in the same plane, but I prefer that the partitions 69 and 70 terminate in sharp upper edges 71 and 72. (See Figs. 15, 16 and 21.) Also, I prefer to bowl or arch in the front and rear ends of the three chambers 66, 67, and 68 from the bottom to the top, so that their upper open ends are smaller than their lower open ends. (This shows clearly in Figs. 21 and 22.) The body member 63 is preferably relieved at each end of the center chamber 67 by cup-like depressions, 73 and 74 (see Figs. 13 and 21), as an aid to the pivotal support of the chuck 64, explained below.

45 Wire or rod electrodes 76, 77, and 78 pass through the three chambers 66, 67, and 68, and lead out therefrom through sealed openings in the body member 63. Additional electrode surface area may be obtained by bending the electrodes 76, 77, and 78, substantially as shown in the drawings. This also serves to relieve stresses that may be set up when the electrodes are installed. The electrodes 76, 77, and 78 are electrically connected to three terminals 79, 80, 81 which are themselves held by an insulator plate 82 at one end of the housing 61. They may be connected into a circuit of the type shown in Figs. 9 and 10.

60 A rubber or latex closure sheet 83 is cemented to the bottom surface of the member 63, and it effectively seals off the chambers 66, 67, and 68 from each other at their lower end. (See Figs. 13, 15 and 16.) The chambers 66, 67, and 68 are substantially filled with the electrolyte 14, though a small quantity of air is permissible where a liquid electrolyte 14 is used. Then the upper end of the body member is closed by a diaphragm 84. (See Figs. 11, 13, 15, 16 and 19.) The diaphragm 84 is cemented to the outer border of the body member 63, but not to the sharp edges 71 and 72, because the diaphragm 84 cooperates with the edges 71 and 72 to form variable area orifices between the chambers 66 and 67 and between the chambers 67 and 68. Preferably the diaphragm 84 is made from latex rubber, such as dentists use for a dental dam. It

and the sheet 83 may both be about 0.010 inch thick. The soft elastic gives an almost perfect response, following modulation up to 15 kilocycles and even higher. The fluid 14 effectively damps the diaphragm 84 and chuck 64 to prevent the formation of secondary impulses due to recovery of the elastic and to the naturally resonant frequency of the chuck. In this manner the size of the orifices can be varied according to the flexing of the diaphragm 84.

The flexing of the diaphragm 84 is accomplished by the movement of the chuck 64, which transmits the horizontal movement of the needle 65 in the grooves of a record.

The chuck 64 includes a central pivot member 85 and two outrigger rods 86 and 87, parallel to the member 85 and spaced from it. (See Figs. 11, 12, 13, 15, 16, 19, and 20.) The pivot member 85 is relieved in the center and sharpened at each end to give slightly blunt pivot surfaces 88 and 89. These pivot members 88 and 89 rest on top of the diaphragm 84 and bear it against the body member 63. The cup-shaped recesses 73 and 74 provide relief so that only the pivots 88 and 89 themselves will bear against the body 63 (through the diaphragm 84). As shown in Fig. 19, brackets 90 and 91 are provided to hold the chuck 64 in alignment adjacent the pivot members 88 and 89. Soft gum rubber members 92 and 93 lie between the member 85 and the brackets 90 and 91 so that there will be adequate resiliency and give.

The rods 86 and 87 are positioned to lie parallel to and just outside the sharp edges 71 and 72. (See Figs. 15 and 16.) When the needle 65 moves from side to side in the record groove, the chuck 64 pivots on members 88 and 89, and the rods 86 and 87 flex or release the portion of the diaphragm 84 which they bear against. This produces a change in the size of the orifices between adjacent chambers, and since the current passage is quite narrowly concentrated, a change in the size of the orifices produces a definite modulation in the voltage drop between adjacent cells or chambers. The positioning of the electrodes is not critical but the location shown here is ideal for good response.

In order to hold the pickup 60 firmly in the housing without affecting the pivot points 88 and 89, a plurality of soft rubber snubbers 95 may be affixed to the diaphragm 84 directly over supporting areas of the body member 63. An indented portion 96 of the plate 62 contacts these snubbers 95 and holds the pickup unit firmly. This pressure also helps to maintain the seal of the diaphragm 84 at the extremities of each knife edge 71 and 72.

The operation of the modified device is substantially the same as that of the form shown in Figs. 1 to 8. A potential is set up across the electrodes 76, 77, and 78, preferably about one-half to one volt, and the changes of voltage of the center electrode 77 are amplified electronically. As the needle 65 moves horizontally across the grooves, the chuck 64 pivots from side to side. The outriggered flex rods 86 and 87 press against the diaphragm 84, and this pivotal movement increases the pressure on one side while decreasing it on the other. The vertical components may be balanced out of the circuit as explained above. The orifices between the center chamber 67 and the side chambers 66 and 68 vary in size, and as a result the voltage drop across each orifice varies. The diaphragm 84 is responsive to minute changes, and responsive to all the modulations. The resistance of each orifice and the proportion-

ate voltage drop are therefore similarly responsive, while the extraneous effects (e. g. vertical movement) are canceled out. The resultant purified electrical modulations may be amplified as much as desired.

The structure of the pickup 60 has some advantages over that of pickup 10 in that the placement of the working gaps on the upper surface of the plastic body affords a somewhat improved high frequency response as well as freedom from sediment settling in the working gaps.

The pickups 10 and 60 are very responsive. Yet they are light in weight. They exert less needle pressure on the record than most crystal or magnetic pickups, and they have the advantage of canceling out the extraneous effects of vertical movement. The device is simple and capable of quantity production at a price well below that of pickups which give a comparable accuracy of reproduction.

Another application of the principles of the invention is shown in Figs. 23 to 26. Here practically the same unit as that shown in Figs. 11 to 22 is used as a microphone.

The microphone includes a hollow housing 100, which is supported on a stand 101. The housing 100 is closed on all sides except the front, which is covered by a wire screen mesh protector 102, as is conventional.

The body member 63 may be cemented or otherwise secured inside the housing 100, in a horizontal position as shown, or may be positioned otherwise. The member 63 is identical to the body member 63 described above and shown in Figs. 11 to 22, having the three chambers 66, 67, and 68 and their electrodes 76, 77, and 78. The electrolytic fluid 14 is contained by the body member 63, the closure sheet 83, and the latex diaphragm 84.

A microphone diaphragm 105, comprising a thin strip of metal such as aluminum foil, is supported on a cross-shaped chuck 106 which functions in a manner similar to the chuck 64. The diaphragm 105 may be dimpled at 107 and 108 for additional stiffness, and its lower edge 109 may be cemented on the central pivot member 110 of the supporting member 106. Supporting vanes 111 and 112 may extend out perpendicularly from the diaphragm 105, and these may be cemented or otherwise secured to the cross arm 113 of the chuck 106.

Sound vibrations will produce corresponding movement of the diaphragm 105, and this will cause the chuck 106 to rock back and forth on its pivot member 110. The pivot member 110 may be mounted exactly as the pivot member 85, described above, so that it will rock in response to the vibration of the diaphragm 105, on pivot points which are held beneath end brackets 115 and 116.

The brackets 115 and 116 also hold the ends of two spring members 117 which exert downward pressure on the latex diaphragm 84 through the sponge rubber pads 118. By this means the diaphragm 84 effects a seal with the partitions 71 and 72 except at the space between the rubber pads 118.

The extremities 120 and 121 of the chuck cross arm 113 extend between the pads 118. Rocking of the chuck 106 raises and lowers the cross arm extremities 120 and 121, and they act on the latex diaphragm 84 to vary the size of the orifices between the chamber 67 and the chambers 66 and 68. The relatively smaller size of the orifices increases the effect of air pressure vibrations on the variations in orifice size, so that good sensi-

tivity is obtained by this construction. The wiring diagram may be similar to that for the pickup unit.

The sound vibrations cause the upright diaphragm 105 to vibrate and to rock the chuck 106. This rocking correspondingly varies the size of the orifices between the chambers. The variation in the size of orifices produces a corresponding variation in resistance between the chambers, and this in turn varies their potential in the manner already explained.

Figs. 27 to 30 show a modified form of control device 150 which may be used where a considerably greater voltage output is required. In this modification, several sets of cells or chambers are arranged in tandem and a common actuating member controls the multiple orifices. The output lead lines from each group of three cells are so connected that their effects are added.

The control device 150 includes a body member 151 in which there are a plurality of rows of chambers, three chambers in each row. Here three rows 152, 153, and 154 are shown, the numbering beginning at the left of Fig. 27. The first row 152 includes chambers 161, 162, and 163. The two side chambers 161 and 163 are next to and communicate with the center chamber 162 through variable-size orifices as a diaphragm 155 is flexed. The second row 153 includes chambers 164, 165 and 166, and the third row 154 includes chambers 167, 168, and 169. All of the chambers contain the fluid 14, and all of them have their respective electrodes 171-179. The electrode connections will be explained later in connection with the circuit.

A chuck 180 has a center pivot arm 181 and as many cross arms as there are rows: in this case there are three cross arms 182, 183, and 184. Rocking of the chuck 180 in a manner similar to that already described in connection with the chuck 64 is produced by movement of a needle 185. The ends of the cross arms 182, and 183, and 184 vary the orifices between the chambers 161-169. Only the chambers in one row are connected with each other; the chambers of different rows are isolated from each other.

The circuit shown in Fig. 30 is illustrative of what can be done. For simplicity, three batteries 192, 193, and 194 are shown, placing a potential across the side or outer chambers in each row 152, 153, and 154. In the row 152, the battery 192, places a potential across the electrodes 171 and 173 in the side chambers 161 and 163.

In the row 153, the battery 193 creates a potential across the electrodes 174 and 176 in the side chambers 164 and 166. In the row 154, the battery 194 creates a potential across the electrodes 177 and 179 in the side chambers 167 and 169.

The center electrode 172 in chamber 162 of row 152 may be connected to one of the outer electrodes 174 of the next row 153. Similarly, the center electrode 175 of row 153 is connected to the corresponding outer electrode 177 of row 154. The resultant output between the electrode 171 and the electrode 178 will have an amplitude three times that across any one of the rows 152, 153, and 154. Output multiplication in this manner is limited only by the mechanical and electrical complexity which is incurred by increasing the number of cell sets.

The control device of this invention is capable of still further uses, of which five additional examples will be listed here:

(1) Referring to Fig. 10 if the battery 54 is

replaced with a source of alternating potential such as an audio or a R. F. oscillator, then the vibrations of the needle 30 or diaphragm 105 would serve to modulate the amplitude of alternating potential appearing on the output electrode 29. The pickup could then function as a low level modulator for a radio transmitter.

(2) Still referring to Fig. 10 if an alternating potential is impressed across the electrodes 29 and 28, through a capacitor of appropriate size, then the phase of the voltage appearing across the electrodes 29 and 28 can be made to vary with the movement of the pickup needle 30. Thus the pickup can constitute a source of phase modulation for frequency-modulated or phase-modulated radio frequency transmission. Frequency modulation can also be accomplished by connecting the electrodes 28 and 29 (Fig. 10) in one leg of a Wien bridge or a similar oscillator circuit.

(3) Still referring to Fig. 10, if a resistor of proper size (e. g., 200,000 ohms) is connected in series with the lead 24, between the battery 54 and the electrode 27, then laterally responsive and vertically responsive outputs may be separately and simultaneously obtained from the pickup. The laterally responsive output will appear on the electrode 29 and the vertically responsive output will appear on the electrode 27.

(4) The invention is also readily adapted to perform as a strain gauge, vibration pickup, sensitive limit control, and other similar instruments.

(5) The voltage output of the pickup is readily controlled by the applied D. C. potential. This feature may be used to adapt the output of the pickup to the gain of the associated amplifier.

(6) The device may also be used in a submarine sound pickup wherein it can be adapted for underwater locating work and for use in depth finding devices.

Still other advantages and uses will be apparent from the above description, in accordance with which I claim as my invention:

1. In a control device for electric circuits, the combination of a body member of insulating material having three chambers, said chambers including means for retaining a current conducting fluid, an electrode in each of said chambers, two variable-area orifices having means for connecting one of said chambers to each of the other two, whereby the resistance between the electrodes is varied as the size of the orifices varies; and means for varying said orifices in tandem, so that one is widened to a greater area as the other is narrowed to a smaller area, and so that an increase in resistance through one orifice is balanced by a decrease in resistance through the other orifice.

2. In a control device for electric circuits, the combination of a body member of insulating material having three chambers, said chambers including means for retaining a current conducting fluid, an electrode in each of said chambers, two variable-area orifices having means for connecting one of said chambers to each of the other two whereby the resistance between the electrodes may be varied, and means to vary said orifices in tandem in response to externally originating motion, so that one orifice is widened as the other orifice is narrowed, whereby the increase in resistance through one orifice is balanced by a decrease in resistance through the other orifice.

3. A control device for electric circuits com-

prising a body member of insulating material having a center chamber and two side chambers therein, an electrode in each of said chambers, electrolytic fluid in said chambers, means defining a variable area orifice between said central chamber and each of the two side chambers to which orifice said fluid has free and unobstructed access at all times, and means for varying in tandem the area of said orifices in response to externally originating motion, so that one said orifice is widened as the other said orifice is narrowed and thereby the increase in electrical resistance through one said orifice is always balanced by a corresponding decrease in electrical resistance through the other said orifice.

4. A control device for electric circuits comprising a body member of insulating material having a center chamber and two side chambers therein, an electrode in each of said chambers, electrolytic fluid in said chambers, means defining a variable area orifice between said central chamber and each of the two side chambers, and means to vary the area of said orifices in response to externally originating motion, the variations in said orifices being maintained in balanced phase opposition by said means.

5. A control device for electric circuits, comprising a body member of insulating material, said body member having three chambers therein; an electrically conductive fluid in said chambers; an electrode in each of said chambers and having terminal connections outside said chambers; a flexible rubber diaphragm covering an open end of said chambers, and cooperating with the body member to provide between a portion of said diaphragm and a portion of said body member an orifice between one said chamber and each of the other two chambers, the area of each said orifice being varied according to the flexing of said diaphragm; an actuating member pivotally mounted and having two portions that bear against said diaphragm, so as to flex said diaphragm in the vicinity of each said orifice and thereby vary their areas substantially equally and oppositely so that an increase in one area is simultaneously balanced by a decrease in the other area; and means mounted on said actuating member to transmit externally originating motion thereto.

6. The device of claim 5 in which the diaphragm-flexing portions of said actuating member are equidistant from the pivot arm thereof and in which said orifices are likewise equidistant therefrom so that the variations in said orifices occur in phase opposition to each other.

7. A control device for electric circuits, comprising a body member of insulating material, said body member having three chambers therein; an electrically conductive fluid in said chambers; an electrode in each of said chambers and having terminal connections outside said chambers; a flexible diaphragm covering an open end of said chambers and cooperating with the body member to provide an orifice between one said chamber and each of the other two chambers, the area of each said orifice being varied according to the flexing of said diaphragm; and an actuating member, pivotally mounted so that part of it bears on said diaphragm adjacent the partitions between said chambers, whereby movement of said member on its pivotal mounting will flex said diaphragm and vary the orifices between said chambers.

8. The device of claim 7 in which a phono-

graph needle is mounted in said actuating member, so that the device will function as a phonographic pickup.

9. The device of claim 7 in which a voice-responsive diaphragm means is mounted on said actuating member, whereby said device will function as a microphone.

10. The device of claim 7 in which the chamber that is joined to the other two chambers is located centrally between them.

11. The device of claim 10 in which said central chamber is cylindrical and in which the actuating member includes an annular pivotal mounting on said housing and an annular ring 15 which bears against the diaphragm adjacent the walls of said outer cylindrical chamber so as to widen the orifice between the center chamber and one of said other chambers when the actuating member is moved laterally, and at the same time to narrow the orifice between the center chamber and the remaining chamber.

12. The device of claim 7 in which the partition walls between chambers terminate in a sharp edge adjacent the diaphragm at the locus 25 of each orifice.

13. A control device for electric circuits, including in combination: a body member of insulating material, said body member having three chambers therein parallel to each other; an electrically conductive fluid in said chambers; an electrode in each of said chambers and having terminal connections outside said chambers; a flexible diaphragm covering an open end of said 30 chambers and cooperating with the body member to provide an orifice between one said chamber and each of the other two chambers, the area of each said orifice being varied according to the flexing of said diaphragm; and an actuating member, pivotally mounted in an axial line along the center chamber and having two rods secured parallel thereto and bearing on said diaphragm adjacent to the partitions between chambers, whereby movement of said member on its 35 pivotal mounting will flex said diaphragm and vary the orifices between said chambers.

14. In a control device for electric circuits, the combination of a body member of insulating material having two spaced chambers, said chambers having means for retaining a current conducting liquid, a third chamber adjacent the two spaced chambers of said body member also having means for retaining a quantity of said current conducting liquid, means defining two variable area orifices one of which makes the connection between each of said spaced chambers respectively and the said third chamber, the area of said orifices being responsive to externally originating motion and means for varying said orifices in tandem, whereby an increase 50 in the area and decrease in the electrical resistance at one orifice is simultaneously balanced by a corresponding decrease in the area and increase in the electrical resistance at the other orifice.

15. A phonographic pickup, comprising a housing; a body member of insulating material secured within said housing, said body member having three chambers therein; an electrically conductive fluid in said chambers; an electrode in each of said chambers and having terminal connections outside said chambers; means defining orifices between one of said chambers and the other two chambers; a phonographic needle holding means; means to vary the area of said 75

orifices in response to the movement of said needle holding means; and means connected to said orifice-area-varying means to maintain the variations in said orifices in phase opposition to each other.

16. A microphone comprising a housing; a body member of insulating material secured within said housing, said body member having three chambers therein; an electrically conductive fluid in said chambers; an electrode in each of said chambers and having terminal connections outside said chambers; a flexible diaphragm covering an open-end of said chambers, and co-operating with the body member to provide an orifice between one said chamber and each of the other two chambers, said orifices being varied in area according to the flexing of said diaphragm; a pivotally mounted actuating member having side portions each in contact with said diaphragm over one said orifice and adapted to flex said diaphragm over one said orifice and to relax said diaphragm over the other said orifice when said actuating member swings on its pivot; and a thin diaphragm strip supported by the actuating member at one edge and adapted to vibrate in response to incoming sound, so as to impart lateral movement to said actuating member.

17. A control device for electric circuits comprising a body member of insulating material having a plurality of rows of chambers therein, each row having a center chamber and two side chambers therein, an electrode in each of said chambers, electrolytic fluid in said chambers, a variable area orifice between said central chamber and each of the two side chambers, and common means to simultaneously vary the areas of said orifices in response to externally originating motion.

18. The device of claim 17 in which the electrode of the center chamber of each row except one is connected to the electrode of a chamber on one side of the next adjacent row.

19. A control device for electric circuits, comprising a body member of insulating material, having three chambers therein separated by partitions; an electrically conductive fluid in said chambers; an electrode in each of said chambers, having terminal connections outside said chambers; a flexible rubber diaphragm secured around its rim to said body member, covering an open end of said chambers, and overlying the partitions between said chambers so that flexing of said diaphragm adjacent said partitions provides an orifice of communication between adjacent chambers that is varied in size according to the flexing of said diaphragm; and an actuating member, pivotally mounted so that part of it bears on said diaphragm adjacent said partitions, whereby movement of said member on its pivotal mounting will flex said diaphragm and vary the size of orifice between said chambers.

20. A control device for electric circuits, comprising a body member of insulating material, having three chambers therein separated by partitions; an electrically conductive fluid in said chambers; an electrode in each of said chambers, having terminal connections outside said chambers; a diaphragm secured around its rim to said body member, covering an open end of said

chambers, and overlying the partitions between said chambers so that movement of the portions of said diaphragm adjacent said partitions provides an orifice of communication between adjacent chambers that is varied in size according to the movement of said diaphragm portions; and an actuating member, pivotally mounted so that part of it bears on said diaphragm adjacent said partitions, whereby movement of said member on its pivotal mounting will move said diaphragm portions and vary the size of orifice between said chambers.

21. A control device with output multiplication for electric circuits including in combination a body member of insulating material, said body member having a plurality of rows of chambers, each row having a center chamber and two side chambers therein; an electrically conductive fluid in said chambers; an electrode in each of said chambers and having terminal connections outside said chambers, the electrode from the center chamber of each row excepting one being electrically connected to the electrode in one side chamber of the succeeding row, all said connected side chambers being on the same side of said center chambers; a flexible diaphragm covering all of said chambers and co-operating with said body member to provide an orifice between the said center chamber in each row and each of the side chambers of said row, the area of each said orifice being varied according to the flexing of said diaphragm; and an actuating member mounted pivotally and having cross members at each row that bear on said diaphragm adjacent said orifices, whereby movement of said member on its pivotal mounting will cause the diaphragm to be flexed on one side of the center chambers and thereby to narrow the orifice between the center chamber and one of the side chambers and will simultaneously relax the diaphragm on its other side and widen the orifice between said center chamber and the other said side chamber, said rows of chambers thereby serving to amplify and multiply the electrical output which is obtained from the electrode for the center chamber of the last said row.

HARRY C. WARNER.
